UNITED STATES PATENT OFFICE.

FREDERICK DIEHL, OF ELIZABETH, NEW JERSEY, ASSIGNOR TO THE SINGER MANUFACTURING COMPANY, OF ELIZABETH, NEW JERSEY, A CORPORATION OF NEW JERSEY.

ELECTRIC SEWING-MACHINE OUTFIT.

Original application filed October 8, 1925, Serial No. 61,170. Divided and this application filed October 19, 1925. Serial No. 63,527.

This invention relates to a sewing machine table of the so-called "library" type which, although specially constructed for the support and operation of a sewing machine, has 5 the neat and graceful appearance of a library table when not in use, with nothing conspicuous to suggest its relation to machinery.

Sewing machine tables of this character 10 have heretofore commonly been of the "drop-head" type; i. e., adapted to support the sewing machine head with its cloth-plate substantially flush with the table-top in such a way that it can be lowered into a cavity 15 in the table through an opening in the table-top when not in use. The sewing machine head of a drop-head outfit is not adapted for portability and is intended to remain at all times attached to its supporting table.

20 To meet the requirements of the trade for a portable sewing machine which may be transported as hand-baggage, it has been customary to provide a hand-carrying case for the sewing machine head, such case comprising portable base and cover sections with 25 releasable means for securing the cover to its base section. To operate a portable sewing machine it is usual to station it upon an ordinary table; whereby the cloth-plate of 30 the machine is elevated above the surface of the table a distance equal to the thickness or depth of the portable base.

An object of the present invention is to 35 provide improved means for supporting, operating and controlling a sewing machine of the portable type, such means being in the nature of an accessory to a portable sewing machine which may be used to afford, in connection with such portable sewing machine, operating characteristics heretofore 40 inherent in drop-head outfits only. Other objects of the invention will in part be obvious and in part be hereinafter more fully described.

45 To the attainment of the ends in view, a sewing machine table, preferably of the four legged type having no cross braces or tie rods between the legs, is provided with an aperture in its top to removably receive the 50 base-section of the machine carrying case which rests upon supporting means so spaced below the table-top that the sewing machine cloth-plate is substantially even with the

table-top, as in a drop-head outfit. A manual control mechanism for the sewing machine motor is permanently installed in the table and preferably comprises a treadle element detachably connected with the lower end of one of its legs, which latter is preferably of hollow or longitudinally channeled 60 construction to receive and conceal an operative connection extending upwardly from the pedal. The manual control mechanism, whatever its form may be, is connectible to and disconnectible from the usual motor-controller in the portable base section of the sewing machine, and preferably includes a connection projectible across and below an edge of the table-top aperture into a hole in the portable base section of the sewing machine, whereby withdrawal of such connection removes all obstruction to removal of the machine and its portable base from the table. The control mechanism is of lightweight non-bulky construction and is un- 75 encumbered by connecting wires. Furthermore its operative position relative to the table is fixed, and consequently is easily found by the operator. Still further, there is no danger of tipping it over, as in the case 80 of a portable foot controller which rests upon the floor.

In the accompanying drawings, Fig. 1 is a transverse vertical section through a library table sewing machine outfit embodying the invention. Fig. 2 is a fragmentary bottom plan view, partly in section, of the parts shown in Fig. 1. Fig. 3 is a view on the line 3, 3, Fig. 1, with the sewing machine removed. Fig. 4 is a fragmentary view of the parts, similar to Fig. 1, but showing the connection to the sewing machine controller as broken. Fig. 5 is a bottom plan view of the guide for the shiftable connector element. Fig. 6 is a perspective view of the shiftable connector element. Fig. 7 is a perspective view showing the shiftable connector element in operative engagement with the controller rock-shaft. Fig. 8 is a vertical section through the lower end portion of the hollow leg of the table. Fig. 9 is a section on the line 9—9, Fig. 8. Fig. 10 is a perspective view of the detachable pedal member; and Fig. 11 is a disassembled perspective view of the pedal shaft, cam-shaft, 100 and cam-shaft bearing.

In the accompanying drawings, 1 represents a sewing machine table having a top 2 and detachable legs 3, 3', end walls one of which is shown at 4, front wall 5 and rear wall 6, the space within such walls constituting a cavity within which is mounted the sewing machine supporting shelf 7. The legs 3, 3' are removably secured by screws 3^a to the iron braces 3^b which join the ends 10 of the table skirt members or walls 4, 5 and 6. The sewing machine, which is of the portable type, comprises the usual sewing head 8, motor 9 and hollow wooden base member 10 of the usual carrying case. The 15 motor 9 is preferably constructed and mounted substantially in accordance with the disclosure in the Diehl et al. Patent No. 1,488,234, of March 25, 1924. The base member 10 of the carrying case is received within 20 the aperture 11 in the table top 2 and has mounted within it a controller or rheostat 12 preferably of the compressible carbon pile type disclosed in the application of D. H. Chason, Serial No. 750,734, filed Nov. 19, 25 1924, and in my co-pending application Serial No. 61,170, filed Oct. 8, 1925, of which this application is a division. Such a controller includes a metal base 13 having at one end an upstanding wall 14 carrying a 30 bearing 15 for the controller operating rock-shaft 16. For the purposes of the present disclosure it is sufficient to explain that a limited rocking movement of the shaft 16 varies the electrical resistance of the rheostat 35 12 connected in the circuit of the motor 9 and thus controls the speed of such motor; the speed of the motor increasing when the rock-shaft 16 turns in one direction and decreasing when it turns in the other direction. The shaft 16 has fixed thereon a collar 17 having a tooth 18 and is accessible 40 through the aperture 16' in the portable base 10. The sewing machine and motor, together with the base 10, rest as a removable 45 unitary assembly upon the shelf 7; the base 10 being received within the aperture 11 in the table-top with the upper surface 19 of the base flush with the table-top.

Concealed within the hollow leg 3' is a rod 50 20 which slides in bushings 21, 22 and the lower end of which rests upon the flat cam-face 23 of the cam 24 journaled in the bearing sleeve 25 set into the horizontal aperture 26, Fig. 9, at the lower end of the leg 3'. The cam 24 is formed at one end with a tooth 55 27 adapted to be engaged by the tooth 28 of a detachable pedal. The pedal preferably comprises a pedal-arm 29 having at its free end a lateral extension 30 for engagement by 60 the operator's foot. The pedal-arm 29 has fixed to its opposite end the enlarged cylindrical head 31 of a shaft-section 32 to which a tubular shaft-section 33 is fixed by means 65 of the pin 34. The shaft-section 33 is adapted to be slipped over the cam-shaft 35 so that

its tooth 28 will engage the tooth 27 of the cam-member 24.

To afford reaction pressure for the pedal there is preferably provided a floor rest 36 having a foot 37 and bearing boss 38 journaled on the shaft 32. A spring 39 is coiled around the shaft-head 31 and is anchored at one end 40 to the arm 29. The other end of the spring 39 bears against the ear 41 of the member 36. When the pedal 29 is depressed 70 the cam-face 23 will lift the rod 20 which has fixed to its upper end portion a lateral arm 42, Fig. 3, extending into the cavity of the table through the slot 43 in a guide-plate 44. A spring 45 surrounding the rod 20 75 within the table-leg and bearing downwardly upon the hub of the arm 42 insures retention of the rod 20 in engagement with the face 23 of the lifting cam 24. The arm 42 carries an adjustable lifting screw 46.

Hinged at 47 on the bracket 48, is a lever 49 having an enlarged end 50 upon which rests the lower end of an inclined arm 51 fixed to the rocking and endwise movable shaft 52 which is journaled in the bracket 53; the screw 46 being in lifting engagement with the lever 49. The shaft 52 is projected into an aperture in the machine base 10 and over the controller rock-shaft 16 and is formed with coupling means in the form of an end shoulder 54, Fig. 7, which engages complementary coupling means in the form of the tooth 18 of the collar 17. The rod 20, when lifted, will swing the lever 49 upwardly and lift the inclined arm 51, thus rocking 95 the shaft 52 and the controller-shaft 16.

When the outfit is not in use the shaft 52 may be withdrawn from the controller rock-shaft by means of the handle 55 and turned to carry its arm 51 clear of the lever 49 100 and the shank of the handle 55 into engagement with the retaining notch 56 in the bracket 53, as shown in Fig. 4; the withdrawal of the shaft 52 being effected against the pressure of the spring 57. In this position of the parts, the end of the shaft 52 is clear of the base 10 so as not to interfere with the removal of the unitary portable sewing machine assembly from its position 110 on the shelf 7. The shaft 52 is also disconnected from the pedal mechanism.

The controller operating mechanism thus includes an element carried by the table and projectible into the sewing machine base for connection with the motor-controller, which element may be withdrawn to permit ready removal of the sewing machine from the table.

The table may be shipped with the legs removed and readily re-assembled for use 125 by one not possessed of special training or mechanical skill; the mere act of attachment of the hollow leg 3' to the table correctly locating the screw 46 relative to the respective coacting follower element 49.

Having thus set forth the nature of the invention, what I claim herein is:—

1. A sewing machine table having a recessed top, a sewing machine of the portable type seated within said recessed top and including a sewing head, motor, portable base and motor-controller mounted in and above the bottom of said base, said sewing head and base being removable from the table as a unitary assembly, and a manually operated mechanism permanently mounted in said table and including a connection projectible across and below an edge of said recess and into said portable base for operative engagement with said motor-controller, said connection being withdrawable to permit removal of the portable sewing machine unitary assembly. 50
2. An electric sewing machine outfit comprising a table having an apertured top, a sewing machine of the portable type removably received within said apertured top and comprising a sewing head, a portable base therefor, a motor for driving the sewing machine and a motor speed-controller mounted within and above the bottom of said portable base and including a controller rock-shaft accessible through an aperture in a side-wall of said base, and controller operating mechanism permanently carried by said table independently of said portable base and including an element removably projectible into the aperture of said base for operative connection with said controller rock-shaft. 55
3. A sewing machine table having an apertured top, a sewing machine of the portable type removably received within the aperture in said top and including a sewing head, portable base, motor and motor-controller, the latter being mounted in said portable base and including an operating rock-shaft accessible through an aperture in said base, a manually operated rocking and endwise movable shaft journaled in said table in alinement with said controller operating rock-shaft, and means for coupling said shafts, said manually operated shaft be- 60
- ing slidable to permit its withdrawal from the aperture in said base prior to removal of the sewing machine from the table. 65
4. A sewing machine outfit comprising a table, a portable electric sewing machine seated as a unitarily removable assembly on said table and including a sewing head, portable base, motor and motor speed-controller, manually operated means permanently carried by said table, and a coupling device for disconnectably connecting said means to said controller, said coupling device being shiftable to an inoperative position in which it is disconnected from both the controller and said manually operated means. 70
5. A sewing machine table having a top and legs, said top being apertured to receive the base of a motor-driven sewing machine of the portable type, a shelf carried by said table below said aperture and adapted to support the sewing machine, and manually operated means permanently installed in said table and including a rock-shaft endwise movable for projection into an aperture in the sewing machine base and connection with a motor-controller within said portable base. 75
6. The combination with a portable electric sewing machine including a portable base, sewing head, motor and motor-controller mounted in said base and having an operating rock-shaft accessible through an aperture in the side wall of said base, of a table having legs and a top apertured to removably receive said base, and manual controller operating mechanism permanently installed in said table and including a pedal mounted on one of the table legs, and pedal operated connections including a rod concealed in the pedal carrying leg, and coupling means operatively connected to said rod and projectible into the aperture in said base for connection with the controller operating rock-shaft. 80
- In testimony whereof, I have signed my name to this specification. 85

FREDERICK DIEHL.
